COMPOUND FLOOR STRIP

Application filed February 8, 1930. Serial No. 426,882.

This invention relates to improvements in dividing strips of the type employed in the construction of terrazzo and similar floors where the floor is divided into a number of panels arranged according to a predetermined design.

Terrazzo, granolithic and similar floors generally comprise a lower or foundation bed made of concrete or cement or mortar 10 or other suitable material, and an upper or finishing layer generally consisting of a mixture of marble chips and cement, by means of which a good durable surface may be obtained as well as pleasing designs and 15 color effects of a practically unlimited variety.

The upper layer which is generally placed in position after the foundation layer has been allowed to harden to a sufficient degree 20 of consistency, is generally divided into a number of panels or units in a predetermined arrangement, which are obtained by outlining the desired design by means of dividing strips placed on or through the foundation 25 layer.

The strips employed are generally made of relatively soft metal such as brass for instance, but are also at times made of different materials according to the ornamental requirements of the design and color scheme 30 to be produced.

As a rule however, the metal employed is apt to be considerably more expensive than steel, and therefore it is desirable to substitute steel or some other inexpensive material for the part of the strip which is embedded into the floor material and which is not likely to show even after the floor has 35 been subjected to considerable wear.

In a patent entitled Dividing strip granted to me May 28, 1929, #1,715,193, I have described and claimed a strip composed of two sections interlocking with each other by means of male and female joints formed by their inner edge portions. Furthermore, in a copending application entitled Terrazzo floor strips, Serial No. 376,809, I have described and claimed a somewhat similar strip in which the joint portions of the strip extend laterally at one side thereof, this construc-

tion tending to increase the rigidity of the structure and doing away with the necessity of providing additional anchoring and positioning means.

The strip illustrated and described in the 55 said application is made in unitary form, the two sections of which the strip is composed being permanently joined to each other by a dovetailed or equivalent joint.

I have found that in practice the type of 60 construction advocated in the said application is well adapted for use in connection with extruded sections; but while it is also possible to produce the required joints by bending and forming operations when mate- 65 rial in flat strip form is used, a rather large number of operations is required as well as dies and tools of a somewhat complicated character; so that the cost of production of such strips is not as low as might be desir- 70 able.

I also have found that it is not always necessary in practice that the two sections 75 composing the strip be permanently joined to each other, since shapes may be produced by bending operations which will be automatically locked and anchored in position after the floor material has become hard, even if the two sections can be taken apart previous to the laying of the strip. I have ac- 80 cordingly devised the type of strip forming the subject of the present invention, its primary object being to provide a bimetallic 85 floor strip of a relatively simple construction entailing less labor for its production than other strips of kindred character heretofore in use.

Another object is to provide in a device 90 of the character specified, a new construction of joint between the two sections of which the strip is composed, said joint constituting either a permanent or a detachable connection between the two sections and requiring only simple operations which may be performed with the expenditure of a relatively small amount of labor and by means 95 of tools which can be produced at relatively low cost.

Other objects and advantages of the pres- 100 ent invention will more fully appear as the

description proceeds and will be set forth and claimed in the appended claims.

My invention is illustrated by way of example in the accompanying drawings in which:

5 Fig. 1 is a fragmentary view in perspective of a simple type of strip embodying my invention;

10 Fig. 2 is a fragmentary view in perspective of another strip embodying my invention in a somewhat different form;

15 Figs. 3 and 4 are fragmentary views in perspective of strips of still different designs embodying my invention; and

20 Fig. 5 is a fragmentary vertical cross section of a terrazzo floor showing the strip illustrated in Fig. 1 in position.

25 A strip made according to my invention essentially comprises a lower section made of sheet steel or other suitable relatively inexpensive material and an upper section supported thereby or interlocking therewith, said upper section being made of the material entering into the floor design to be produced and consisting of a strip being bent outwardly to form a horizontal or inclined flange projecting laterally of the body of the strip, said flange forming part of the connection of the upper with the lower section.

30 The basic idea is illustrated in Fig. 1 representing a floor strip composed of an upper section 10 and a lower section 11. The upper section is in the form of a long relatively narrow strip of the thickness required by the floor design, the inner edge portion 12 of said strip being bent laterally of the outer and major portion 13 thereof to form a downwardly inclined longitudinal flange projecting at one side of said strip.

35 The lower strip section has its inner edge portion bent downwardly at one side at 14 at an angle equivalent to that of flange 12 of the upper section.

40 The longitudinal flange thus formed by the bend 14 is then bent outwardly at 15 and inwardly at 16 to form a U-shaped channeled chamber 17 inclined to the body 18 of the said lower section at an angle corresponding to the angle of flange 12, said flange being adapted to register with and to receive said flange as the drawing shows.

45 Flange 12 of the upper section 10 may be inserted within chamber 17 before or after said chamber has been formed, and no connection other than that which may be obtained by frictional resistance between the contact surfaces is needed in order to render the floor strip ready for use. If desired it is even possible to make the longitudinal groove of chamber 17 wide enough to permit of flange 12 being freely inserted therein or removed therefrom.

50 When the floor is laid as shown in Fig. 5, the lower layer 19 of the floor is first

laid upon the floor foundation 20 and then the dividing strip is inserted in position as shown, the upper edge of the flange forming chamber 17 being preferably used as a means of gauging the depth at which the strip is to be inserted within the lower layer 19.

55 When the strip is thus placed in position it may either be in its completed form shown, or else the lower section may be placed in position and the flanged inner edge of the upper section may then be inserted in position within chamber 17 if a loose connection is provided therebetween. The outer or vertical portion 13 of the upper section is preferably as wide as the upper or finishing layer 21 of the floor is deep, and therefore the upper edge 22 of the strip will be flush with the upper surface of said floor.

60 It will be observed that by virtue of this construction the laterally projecting flanges which form the joint between the two sections will effectively act as anchoring means both for the lower and for the upper section after the plastic material of which the floor is composed has become hard.

65 This result is obtained by the use of relatively inexpensive and standard materials such as sheet metal strips, and by the performance of few, simple and relatively inexpensive operations, so that a strip of this character can be produced at a cost which is materially below that of an equivalent product requiring the use of specially shaped extruded bars.

70 The floor strip illustrated in Fig. 2 is similar to the one just described being composed of an upper section having a vertical upper or outer portion 23 and an inner portion bent to form an outwardly inclined flange 24, and a lower section having its inner edge portion 25 adapted to receive flange 24; the difference being that the channeled structure forming chamber 25 is connected to the main or body portion 26 of the lower section by a horizontal tract 27 affording a means of determining the exact vertical alignment of the strip by resting upon the surface of the lower floor layer when the strip is inserted therethrough.

75 An equivalent result may be obtained by forming the two sections of the strip with horizontal instead of inclined interengaging flanges. For instance, in Fig. 3 the upper section is formed into a vertical body portion 28 and a horizontal flange 29 laterally extending therefrom, while the lower section is composed of a vertical or body portion 30 and has its inner edge portion bent outwardly and then upwardly and inwardly to form a horizontal channeled chamber 31 adapted to receive flange 29 as shown. In this case, the lower surface 32 of said chamber can be used as positioning means determining both the depth of insertion and the correct alignment

of the strip, and the rib formed by the chamber itself may be used as anchoring means.

Fig. 4 shows the possibility of inclining flange 33 and the channeled chamber 34 interlocking therewith upwardly instead of downwardly as shown in Figs. 1, 2, this arrangement intensifying to a certain extent the anchoring action. The drawing also illustrates the possibility of using for the upper section a drawn bar composed of a relatively thick head portion 35 and a comparatively thin rib portion 36, this construction being usable to advantage when designs showing relatively wide metal strips are to be produced.

Although in all the examples illustrated the laterally extending flange is shown in connection with the upper section while the channeled rib member or flange interengaging therewith is shown in connection with the lower section it is obvious that these conditions could be reversed and likewise other strips embodying my invention may be made in forms different from those shown without departing from the inventive idea; the drawings will therefore be understood as being intended for illustrative purposes only and not in a limiting sense. Accordingly, I reserve the right to carry my invention into practice in all those ways and manners which may enter, fairly, into the scope of the appended claims.

I claim:

1. A divider strip for terrazzo floors or the like, comprising upper and lower longitudinal sections, one of said sections having at its inner edge an uninterrupted flange extending laterally of the body on one side only thereof, the other section having at least part of its inner edge embracing said flange so as to connect said sections to each other.

2. A divider strip for terrazzo floors or the like, comprising upper and lower longitudinal sections, one of said sections having at its inner edge an uninterrupted flange extending laterally of the body on one side only thereof, the other section having at least part of its inner edge embracing said flange so as to connect said sections to each other, the resulting laterally extending connection being adapted to act as positioning and anchoring means for said strip.

3. A terrazzo or similar floor strip, comprising upper and lower longitudinal sections, the upper section having its inner edge bent to form an uninterrupted flange extending laterally of the body thereof, the lower section having at least part of its inner edge embracing said flange so as to connect said sections to each other.

4. A terrazzo or similar floor strip, comprising upper and lower longitudinal sections, the upper section having its inner edge bent to form an uninterrupted flange extending laterally of the body thereof, the lower

section having at least part of its inner edge embracing said flange so as to connect said sections to each other, the resulting laterally extending connection affording positioning and anchoring means for said strip.
